UNITED STATES PATENT OFFICE.

JOHN CORNELIUS WILSON, OF BOSTON, MASSACHUSETTS.

DISTRICT SIGNALING APPARATUS.

SPECIFICATION forming part of Letters Patent No. 339,960, dated April 13, 1886.

Application filed October 13, 1884. Serial No. 145,399. (No model.)

To all whom it may concern:

Be it known that I, JOHN CORNELIUS WILSON, of Boston, Suffolk county, State of Massachusetts, have invented an Improvement in 5 District Signaling Apparatus, of which the following description, in connection with the accompanying drawings, is a specification, like letters on the drawings representing like parts.

My invention, relating to signal apparatus 10 such as employed for municipal or district telegraph purposes, consists in novel appliances for producing a return-signal for notifying a subscriber at a sub-station that his message has been received at the main or central station, the said return signal not interfering 15 with the other use of the line.

The main signaling apparatus consists, essentially, of signal-boxes at the sub-stations, containing break-wheels or other automatic 20 circuit-breaking devices, and receiving apparatus or registers at the main or central station, of any usual construction.

The appliances for producing the return-signal consists of a receiving signal-instrument 25 at each of the boxes or sub-stations in a normally open or shunted branch of the main circuit while the direct signaling or message is being transmitted from the sub-station to the central office, but which is automatically 30 thrown into the main circuit after such direct signal is completed, the said signaling-instrument being affected by or responding to reversals in polarity at the main station, but unaffected by interruptions in a current of 35 constant polarity, and the apparatus at the main station by which the return-signal is transmitted consists of a pole-changing device, whereby the position of the main battery in the main circuit may be reversed with- 40 out opening the line, so that no effect is produced on the register or apparatus for signaling by breaks or interruptions in the current.

Figure 1 shows, mainly, in diagram a circuit and signaling apparatus embodying this invention; Fig. 2, a plan view of the break-wheel, showing its circuit-connection with the main line and with the instrument for producing the return-signal.

The apparatus is included in a main circuit 45 connecting a main or central station, C, Fig. 1, with any desired number of sub-stations,

A, each containing a signal-box by which telegraphic messages are automatically transmitted to the main or central office in any usual manner. As shown in this instance, the signal-box at each sub-station A contains a break-wheel, *a*, which may be operated by any suitable or usual clock-work or mechanism not herein shown or described, as apparatus of this character in various forms is well-known. 55 The said break-wheel *a*, as shown in this instance, forms a portion of the main circuit which is completed by a contact-spring, *b*, resting on the said wheel, the circuit being broken and the current therein interrupted 60 when each notch passes under the end of the said spring *b* in the usual manner. The spring *b* is connected with the main line 2, leading from the station A toward the main office in one direction, and the break-wheel *a* is connected with the portion 3 of the main line leading to the central office in the other direction, 65 the said main line at the central station passing through signal-receiving apparatus consisting of a relay-magnet, *r*, controlling a register, *R*, 70 by which signals transmitted from the sub-stations are made known at the central office. The main line 2, from one side of main office, is connected with contact-springs *c* and *d*, 75 adapted to make contact, respectively, with two portions, *e* and *f*, of a key or lever, *g*, operated by hand or by a magnet, *h*, in a local circuit controlled by a key, *i*. The two portions *e* and *f* of the transmitting-key or lever are connected by wires 4 and 5 with the opposite 80 poles of the main battery B, and the portion 3 of the main line is connected with contact-springs *k* and *m*, co-operating with the portions *e* and *f* of the transmitting-lever, which when in one position connects the poles of the 85 battery B, through the springs *d* and *m*, with the main line, causing the current to pass therethrough in one direction, and when the said lever is in its other position it connects the same poles of the battery, through the 90 springs *c* and *k*, with the opposite ends of the main line, causing the current to pass therethrough in the opposite direction. These devices constitute a pole-changer of well-known 95 construction, by which the polarity or direction of the current is reversed in the main line without opening or breaking the latter, and 100

consequently without affecting the relay r or receiving apparatus for messages transmitted from the sub-stations. This pole-changer is used by the operator at the main or central 5 station to transmit a return-signal after a message has been received upon the receiving apparatus R from one of the sub-stations A , the said return-signal being received upon or made known by a signaling-instrument, n , at 10 the sub-station. The said receiving-instrument n for the return-signal is shown as of the kind in which the armature o is polarized by a permanent magnet, p , and is pivoted between the poles of an electro-magnet, r , and consequently 15 caused to vibrate when the polarity of the said electro-magnet is changed, as by reversing the direction of the current passing through it. The said magnet is included in a branch, 6 , from the main line 2 , connected 20 with a spring, t , resting on the surface of the wheel a at the side of the spring b , which normally shunts the said branch and magnet r therein, while the notched portions of the periphery of the wheel a are passing beneath the 25 springs to transmit the message to the main office.

The notches by which the signal or message of the box is produced occupy only a portion of its circumference, beyond which the part co-operating with the spring b is cut away or reduced 30 in diameter, as shown at a' , while the portion co-operating with the spring t remains of full diameter, so that the said spring b is removed from the circuit, which will then include the 35 branch 6 , magnet r , and spring t , while the portion a' of the wheel is passing beneath the spring b after the signal has been wholly transmitted from the sub-station to the main office, and during this time the central operator having 40 received the signal or message will operate the key i or pole-changer g a few times, producing a corresponding number of taps on the bell of the signal m .

It is obvious that the herein-described answering-signal is applicable to any kind of signal-box, either those in which the wheel a is rotated by a motor that is wound up from time to time and tripped or released when each signal is sent, or in which the motor is 45 wound for each signal, and, if desired, a multiple signal device might be employed—such as shown in Letters Patent granted to me September 4, 1883, to which reference may be had—in which case the periphery of the wheel a would be removed under both springs b and t for a certain space, to permit the multiple device to operate.

In Letters Patent No. 290,302, granted to me December 18, 1883, an induction-coil was 50 shown normally retained wholly detached from the circuit, but which when the key or transmitter, also therein shown, was depressed, the battery was removed from the main circuit

and connected in the short circuit with the primary coil of the induction-coil, said key or 55 transmitter simultaneously placing the secondary coil of the said induction-coil in the main circuit, so that pulsations or interruptions in the current of the battery passing through the primary coil produced by induction a series of impulses in the secondary coil and main circuit, and such apparatus for return-signaling I do not herein claim.

By the battery-reversing instrument herein described the position of the battery in the 5 main circuit is reversed without opening the line, so that no effect is produced upon the register or apparatus for signaling by breaks or total interruptions in the current, said register or apparatus for signaling being constructed and arranged to respond to reversals in polarity; also, by the battery-reversing instrument herein described a signal of different character is produced than by the pole-changer described in the patent referred to, in 85 this instance it being a series of taps regulated as to their number by the depressions of the key, while in the patent referred to a rapidly-vibrating signal is transmitted, so that if it is desired to employ return-signals of different 90 character in a single system both kinds of pole-changing devices may be employed.

I claim—

1. In an electric circuit, a signal-box or sub-station containing a break-wheel and a 95 polarized signaling-instrument and device for interposing the latter in the circuit after the signal has been transmitted by the break-wheel, combined with a battery-reversing instrument located at the station where the signal of the said break-wheel is received for operating the said polarized signaling-instrument at the sub-station, substantially as described.

2. The notched circuit-wheel a , and contact-springs b and t co-operating therewith, combined with the polarized signaling-instrument connected in a branch between the said springs, and the battery-reversing instrument at the station where the signal produced by the said 110 circuit-wheel is received for operating the said polarized signaling-instrument, the said circuit-wheel having a portion of its periphery notched for its entire width, and another portion of its periphery of full diameter where 115 co-operating with one spring, and of reduced diameter where co-operating with the other spring, substantially as described.

In testimony whereof I have signed my name to this specification in the presence of two sub- 120 scribing witnesses.

JOHN CORNELIUS WILSON.
